(57) **CLAIM**

The ornamental design for a collapsible mobile phone holder, as shown and described.

DESCRIPTION

FIG. 1 illustrates a top-perspective view of the collapsible mobile phone holder of FIG. 1;

FIG. 2 illustrates a bottom-perspective view of the collapsible mobile phone holder of FIG. 1;

FIG. 3 illustrates a top view of the collapsible mobile phone holder of FIG. 1;

FIG. 4 illustrates a bottom view of the collapsible mobile phone holder of FIG. 1;

FIG. 5 illustrates a side view of the collapsible mobile phone holder of FIG. 1;

FIG. 6 illustrates a front view of the collapsible mobile phone holder of FIG. 1;

FIG. 7 illustrates a top-perspective view of the collapsible mobile phone holder of FIG. 8;

FIG. 8 illustrates a bottom-perspective view of the collapsible mobile phone holder of FIG. 8;

FIG. 9 illustrates a top view of the collapsible mobile phone holder of FIG. 8;

FIG. 10 illustrates a bottom view of the collapsible mobile phone holder of FIG. 8;

FIG. 11 illustrates a front view of the collapsible mobile phone holder of FIG. 8;

FIG. 12 illustrates a rear view of the collapsible mobile phone holder of FIG. 8;

FIG. 13 illustrates a left-side view of the collapsible mobile phone holder of FIG. 8;

FIG. 14 illustrates a rear-perspective view of the collapsible mobile phone holder of FIG. 8;

FIG. 15 illustrates a top-side perspective view of the collapsible mobile phone holder of FIG. 17;

FIG. 16 illustrates a bottom-perspective view of the collapsible mobile phone holder of FIG. 17;

FIG. 17 illustrates a top view of the collapsible mobile phone holder of FIG. 17;

(Continued)

FIG. 18 illustrates a bottom view of the collapsible mobile phone holder of FIG. 17;
 FIG. 19 illustrates a front view of the collapsible mobile phone holder of FIG. 17;
 FIG. 20 illustrates a rear view of the collapsible mobile phone of FIG. 17;
 FIG. 21 illustrates a left-side view of the collapsible mobile phone holder of FIG. 17; and,
 FIG. 22 illustrates a top-perspective view of the collapsible mobile phone holder of FIG. 17.
 The broken lines shown in FIGS. 13 and FIGS. 15-22 depict environment that forms no part of the claimed design.

1 Claim, 11 Drawing Sheets
